UNITED STATES PATENT OFFICE.

CHARLES DE QUILLFELDT, OF NEW YORK, N. Y.

BOTTLE-STOPPER EXTRACTOR.

SPECIFICATION forming part of Letters Patent No. 369,046, dated August 30, 1887.

Application filed August 2, 1886. Serial No. 209,776. (No model.)

To all whom it may concern:

Be it known that I, CHARLES DE QUILLFELDT, a citizen of the United States, and a resident of New York, in the county and State of New York, have invented a new and useful Improvement in Bottle-Stopper Extractors, of which the following is a specification.

The object of my invention is to provide a simple, cheap, and efficient tool for opening 10 bottles, applicable to all bottle-stoppers in which the extraction of the cork or stopper proper is dependent upon the swinging aside of a wire bail, or its equivalent, attached to or about the bottle-neck.

15 The invention will be hereinafter fully described, and specifically pointed out in the claim, reference being had to the accompanying drawings, in which—

Figures 1 and 3 are plan views of two modifications of a bottle-stopper extractor constructed according to the present invention, and Fig. 2 is an edge view of Fig. 1. Figs. 4, 20 5, 6, and 7 are elevational views of four different kinds of bail-supplied bottle-stoppers, each 25 closed in the mouth of a bottle, and each view showing my improved opener or extractor applied in position ready to swing the bail aside for releasing and removing the cork or bottle-stopper. Fig. 8 is a detail view (seen in direction of arrows 3 of Figs. 2 and 4) showing 30 the manner in which the ends of the forked lever engage the bottle-stopper bail.

The extractor consists of a shank or handle provided at the end with a fork of two prongs 35 bent or deflected in opposite directions laterally, or diverging from the crotch, and also bent or deflected transversely thereto, both toward the same direction, the ends of the fork-prongs being bent inward in line with and opposite to each other.

40 The tool may be cast in one piece; but it is preferably made of wire, either in one piece, when a single fork is used, or in two pieces secured together, when a double fork is used—that is, one fork at each end of the shank.

A is the shank of the extractor; *cc*, the prongs of the fork-lever; *b*, the crotch or angle between the prongs *c*, and *d* their extreme ends, which are bent inward or toward the crotch and each 45 other, and by which the bail of the bottle-stopper is engaged, in order to be swung aside for

extracting the cork or stopper. Figs. 4, 5, 6, 7 show plainly how to use the instrument.

The fork-lever is simply let down upon the bottle so that it will bear against the bottle-neck, with two points on the inside of the prongs *c* at opposite sides of the crotch, thus forming a fulcrum for the lever, while the inward-bent ends *d* engage the wire bail of the stopper. The handle end is then depressed, as indicated 55 by arrow 1 in Fig. 4, which causes the bail to swing aside, as indicated by arrow 2, thus releasing the stopper.

In order to make the instrument light and strong, as well as cheap, I make it of a wire by 60 bending the latter in the required shape and securing together its free ends at the crotch *b*, either by giving them a slight twist at *a*, as in Fig. 4, or by soldering to them a surrounding metallic band, as at *a* in Figs. 1 and 2.

65 The instrument is made integral of one single piece of wire bent back upon itself, so as to form a loop for the handle, as in Figs. 1, 2, and 3.

70 How the leverage is obtained for swinging the bail aside I have shown in Figs. 4 to 7, inclusive. A reference to Fig. 8 will explain two important points—first, that the instrument will adjust itself to always bring the two ends *d* in contact with the wire bail, and, 75 second, that in depressing the handle *A* the ends *d* have no tendency to slip off laterally from contact with the wire bail. In the said figure the circle *C* represents the outline of the cross-section of the bottle-neck, and *B* 80 the wire bail in cross-section.

75 It will be plainly seen that, owing to the gradual diverging of the prongs *c* at the crotch *b*, the fulcrum-points, or points of contact between the prongs *c* and the bottle-neck surface *C*, will always be so located that the line *xx*, drawn through the axis of the handle *A*, will also go through the center of the bottle-neck *C*, thus causing both of the ends *d* to engage the wire bail simultaneously.

85 It will further be seen that (owing to the fact that the said ends *d* are not bent inward, so as to be in the same axial line *yy*, but are bent toward the crotch *b*, so that their axial lines *gg* and *ff* make an obtuse angle with each other) when the handle is depressed the 90 said ends *d* press upon the wire bail *B* in di-

rection of arrows 4, and of course the counter-action or resistance of the bail is in the opposite direction or in direction of arrows 5, thus insuring a steady grip of the fork ends upon the bail without any tendency to slip off therefrom laterally until the bail is swung aside to release and remove the stopper.

I am aware that a corkscrew has been constructed with two prongs projecting at right angles to the shank thereof, the said two prongs having their ends bent inward to adapt the corkscrew also for use as an extractor, and I do not claim such construction.

Having thus described my invention, what I claim as new, and desire to secure by Letters Patent, is—

A bottle stopper opener consisting of a wire

doubled to form the handle thereof and having its free ends secured together at *a*, as shown, and thence diverging laterally, and deflected 20 transversely both toward the same side of the handle to form the prongs of the fork-lever, the extreme ends *d d* of the prongs being bent inward or toward each other to adapt them to engage the bottle-stopper bail.

In testimony that I claim the foregoing as my invention I have signed my name, in presence of two witnesses, this 29th day of July, 1886.

CHAS. DE QUILLFELDT.
